US0D1027860S

(12) **United States Design Patent** (10) Patent No.: **US D1,027,860 S**
(45) Date of Patent: ** May 21, 2024

(54) **POWER CONNECTOR**

(71) Applicant: **Bizlink Electronic (Xiamen) Co., Ltd.**
Fujian (CN)

(72) Inventors: **Xiangwu Wang**, Xiamen (CN);
Zhongxiang Wang, Xiamen (CN)

(**) Term: **15 Years**

(21) Appl. No.: **29/822,117**

(22) Filed: **Jan. 6, 2022**

(30) **Foreign Application Priority Data**

Jul. 6, 2021 (CN) 202130423756.8

(51) **LOC (14) Cl.** **13-03**

(52) **U.S. Cl.**

USPC **D13/133**

(58) **Field of Classification Search**

FOREIGN PATENT DOCUMENTS

IN 2300870001 * 5/2011

Primary Examiner — Shawn T Gingrich

Assistant Examiner — Justin M. Donaldson

(57) **CLAIM**

The ornamental design for a power connector, as shown and described.

DESCRIPTION

FIG. 1 is a top and right perspective view of a power connector showing our present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom and left side perspective view thereof. The broken lines in the drawings illustrate portions of the power connector which form no part of the claimed design.

1 Claim, 8 Drawing Sheets
